UNITED STATES PATENT OFFICE

2,471,595

MACHINE AND METHOD OF MAKING OIL FILTER PACKS

Albert R. White, Glendale, Calif.

Application May 27, 1946, Serial No. 672,489

14 Claims. (Cl. 57—5)

1

The present invention relates to improvements in a machine and method of making an oil filter pack. It consists of the combinations, constructions and arrangement of parts of the machine, and the steps of the method, all hereinafter described and claimed.

In my United States Letters Patent, No. 2,274,113, granted on February 24, 1942, entitled "Oil refiner pack," I disclose a body of filtering material, such as cotton fabric or waste, that is disposed around a filtering core. The latter includes an outlet pipe for oil passing through the filtering material. This core is suitably keyed to the surrounding filtering material so that rotation of the assembled pack also will turn the outlet pipe. The filtering material is held in proper shape and fastened in place by means of string, which is wrapped around the outside of the pack.

My United States Patent No. 2,453,952, dated November 16, 1948, relating to an "Oil refining foldable pack and casing," illustrates a flexible core having a pack structure, including cotton waste, surrounding the core. The exterior of the pack has string wrapped therearound.

An object of my present invention is to provide a machine that is adapted for placing cotton waste around filtering cores of the character above referred to, and also wrapping string around the pack structure to bind the material in place.

A further object is to provide a machine of the character described that will compress a predetermined amount of filtering material around each of the filtering cores and produce packs having uniform density.

A still further object resides in the provision of an oil filter pack-making machine that is adjustable in order to fashion packs of varying lengths.

More specifically described, I provide an endless belt, which is guided so as to have a depressed portion presented therein. The pre-formed filtering core is rotatably arranged in this depressed portion. A predetermined amount of cotton waste is delivered to this depressed portion of the belt and the latter moves the waste into encircling relation with respect to the filtering core. After the cotton waste is positioned and compressed around the core, string or other suitable binding material is wrapped around the pack to bind the waste in place. Thereafter the drums about which the belt is trained are moved apart so as to allow the oil pack to be removed from the machine.

2

Other objects and advantages will appear as the specification continues, and the novel features of my invention will be set forth in the claims hereunto appended.

For a better understanding of my invention, reference should be had to the accompanying drawings, forming part of this application, in which:

Figure 1 is an elevation of a completed oil filter pack with parts in section;

Figure 2 is an end elevation of a machine constructed in accordance with my invention;

Figure 3 is a transverse sectional view through a portion of the machine, and taken along the line III—III of Figure 4, with the drums arranged adjacent to one another;

Figure 4 is a horizontal section taken along the line IV—IV of Figure 2, with the drums moved apart;

Figures 5, 6 and 7 are vertical sections taken along the lines V—V, VI—VI and VII—VII, respectively, of Figure 4;

Figure 8 is a top plan view of the string-feeding mechanism;

Figure 9 is a vertical section taken along the line IX—IX of Figure 2;

Figure 10 is a perspective view of an operating handle holder; and

Figure 11 is an end elevation of one of the sliding cross-heads, portions being disclosed in section.

While I have shown only the preferred form of my invention, it should be understood that various changes, or modifications, may be made within the scope of the annexed claims without departing from the spirit thereof.

Form of filter pack

Before proceeding with the detailed description, I will describe one form of my oil filter packs in order that the use of the machine may be more readily understood. Of course, I do not wish to be limited to the pack that will be set forth.

In Figure 1, I disclose an oil filter pack indicated generally at A and having a filter core B. The latter includes an oil outlet pipe 1 with a spring 2 secured thereto. A plug 3 is inserted into the end of the spring opposite the pipe 1. Thereafter, several layers of filtering cloth 4 are wrapped so as to enclose the spring 2, plug 3 and a portion of the pipe 1. These layers of cloth are secured in place by cords or strings 5.

Next, a layer of loofah sponge 6 is placed around the filtering cloth 4, and the sponge is anchored in position by cord or string 7. A nail

8 extends through an opening 9 formed in the outlet pipe 1 and projects from both sides of the latter and serves to key the core B to the pack.

The filter core B is preformed before it is inserted into my machine. Suitable filtering material, such as cotton waste 10, is placed around the filter core by the machine, the details of which will be set forth later. This filtering material has a cylindrical outer surface 11 and parallel opposing ends 12 and 13. A pair of strings 14 are wrapped spirally around the outer surface 11 of the filtering pack for holding the cotton waste in place upon the filtering core.

This spiral winding of the strings is accomplished while the pack is disposed in the machine. After the pack is removed, additional strings 15 are wrapped around the assembled pack so as to extend lengthwise thereof and across the opposing ends 12 and 13 of the filter pack.

Construction and operation of machine

Referring now to the machine itself, I provide a supporting frame indicated generally at C. This frame includes upper and lower rails 16 and 17, respectively, which are arranged in pairs at opposite ends of the machine as shown in Figure 9. A fixed bearing block 18 is mounted between each pair of rails, and a shaft 19 is journaled in these blocks. The shaft 19 has a drum 20 fixed thereto, and a driven gear 21 is secured to this shaft.

The upper and lower rails 16 and 17 at each end of the machine are provided with confronting channels 22, which serve as guides for sliding cross-heads 23. The latter rotatably carry a shaft 24 that is mounted in parallel relation to the shaft 19. These shafts maintain their parallel relationship as the cross-heads 23 are moved back and forth in the channels 22. A drum 25 is fixed to and rotated by the shaft 24.

In Figures 2 and 4, I show a motor 26 that is supported on the frame C by means of a bracket-like platform 27. This motor drives a shaft 28 through a flexible coupling 29 and a pair of bevel gears 30. The shaft 28, in turn, has driving gears 31 and 32 secured thereto. The gear 31 meshes with the driven gear 21 previously mentioned, and in this manner the drum 20 is rotated in the direction of the arrow 33 shown in Figures 2, 3 and 7.

A gear 34 is fastened to the shaft 24, and this gear is adapted to mesh with and be driven by the driving gear 32 when the drum 25 is moved into the position shown in Figure 2. It will be noted in Figure 4 that the gears 32 and 34 are out of mesh; accordingly, the drum 25 will not be turned at this time.

An endless belt D is trained around the drums 20 and 25 and has sufficient length to provide a depressed portion 35 in its upper reach. This belt portion is loop-shaped and will cover the major peripheral surface of the pack to be made. The pack A is formed in this depressed portion of the belt when the drums are positioned as disclosed in Figures 2 and 3. Upon separating the drums 20 and 25, see Figures 4 and 7, the pack A is free to be removed from the machine.

In order to move the cross-heads 23 back and forth in their guide channels 22 and thus move the drum 25 relative to the drum 20, I have provided a pair of operating handles 36. The underneath surfaces of these handles are fashioned with notches 37. The latter engage with fixed catches 38 (see Figures 2 and 10) when the drums 20 and 25 are slightly spaced apart, as disclosed

in Figure 3. At this time, the centers of the filter core B and drums 20 and 25 are equidistantly spaced apart.

The handles 36 are pivoted to the sliding cross-heads 23 by pins 39 and connections 40 anchored to the cross-heads. This pivotal arrangement allows the notches 37 to be engaged with or disengaged from the catches 38. When the handles 36 are retracted, the drum 25 is separated 10 from the drum 20, as shown in Figures 4 and 7. The frame C is formed with elongated slots 41 to permit the handles 36 to be raised or lowered relative to the catches.

In Figures 4 and 9, I show a vertically-disposed plate 42 that is fastened to the frame C adjacent to the right-hand end thereof. This plate provides an end wall for the filtering material 10 at the end 13 of the pack A during formation of the latter. An adjustable plate 43 is mounted 20 parallel to the plate 42 and defines an end wall for the pack end 12. Screws 44, or other suitable fastening means, are used for anchoring the plate 43 to a bar 45. This bar extends between front and rear frame members 46 and 47, respectively, these members forming part of the supporting frame C.

The bar 45 has out-turned end pieces 48 that bear against the confronting faces of the frame members 46 and 47 (see Figure 9). These end pieces are recessed, as at 49, so as to receive 30 clamping bolts 50. Plates 51 are fixed to and extend from opposite ends of the bar 45 so as to straddle the frame members 46 and 47. The purpose of these plates is to slidably support the bar 35 45 on the members 46 and 47.

When wing nuts 52 on the clamping bolts 50 are loosened, the bar 45 and its plate 43 may be adjusted toward or away from the plate 42. This allows packs A of different lengths to be formed 40 in my machine. The position of the plate 43 with respect to the plate 42 determines the length of the filter pack.

The adjustable plate 43 has an inclined slot 53 fashioned therein for receiving the outlet pipe 1 of the oil filter core B (see Figures 2, 3, 4, 7 and 9). A block 54 is mounted on the bar 45 and has a recess 55 arranged to receive the projecting end of the outlet pipe. A pin or spindle 56 (see Figure 4) is slidably disposed in the block 50 54 and is adapted to be pushed into the bore of the outlet pipe to support the latter and the filter core B in the depressed portion 35 of the endless belt D. A stop 57 (see Figure 4) limits 55 inward insertion of the spindle 56 relative to the oil outlet pipe.

The method of surrounding the filter core B with the cotton waste 10 now will be described. A predetermined amount of the cotton waste is weighed out, and this will depend upon the length and diameter of the pack to be made and the density desired for the filtering material. The filter core B is supported in the depressed portion 35 of the endless belt D. The drum 20 is turned in the direction of the arrow 33 and the drum 25 is rotated in the same direction, as suggested by the arrow 58. The preweighed cotton waste 10 is fed into space between the drums 20 and 25 when these drums are positioned as shown in Figure 3. The operator delivers this material along the entire length of the pack to be formed; that is, between plates 42 and 43.

The core B is free to rotate in the recess 55 and the spindle 56 serves as a support for the filter core. The incoming cotton waste is fed between the core and the portion d of the endless

belt (see Figure 3). As the belt continues to move, the cotton waste is wrapped around the core B, care being taken that waste is placed along the entire distance between the plates 42 and 43. The depressed portion 35 of the belt compresses the cotton waste as the latter is applied to the filter core, and the filtering material will have uniform density throughout the pack A when the latter is completed. In order to safeguard the operator feeding the material into the machine, I have provided a cover guard 59 that encloses the upper part of the drum 20. This guard is hinged, as at 60, to end plates 61. The guard may be raised into an out-of-the-way position when desired by the operator.

The mechanism for applying the spiral winding of strings 14 around the pack now will be described. The driven shaft 28 has a pulley 62 thereon, which drives a second pulley 63 by means of a belt 64 (see Figure 2). The latter pulley is secured to and drives a shaft 65. A spiral spring 66 is anchored to this shaft so as to turn therewith. I utilize this spring for guiding the strings 14 (see Figure 9) onto the pack and thus cause the strings to be wound spirally around the pack A as the latter is rotated.

The strings 14 are furnished from bobbins 67, and are guided through an eyelet 68. Then the strings pass around pulleys 69 and the free ends 14a (see Figures 1 and 9) are laid lengthwise along the pack A so that these ends will be held in place between the periphery of the untied pack and the endless belt D. Of course, the pack is not rotated at this time. The strings 14 are engaged with the spiral spring 66 near the right-hand end of the latter, as suggested by the broken lines in Figure 9. Certain of the pulleys 69 are adjustable so that tension on the strings may be varied to suit requirements.

Next, the motor 26 is put into operation again and the pack A is rotated. The strings 14 are fed and advanced along the pack by the spring 66, resulting in winding the strings 14 spirally from one end of the pack to the other. The strings now are cut from the unused portions thereof, and these cut ends are tied as at 69', to a previous winding (see Figure 1).

The pack is now ready to be removed from the machine. This is accomplished by disengaging the notches 37 of the handles from the catches 38 and pulling out on the handles. The latter advance the sliding cross-heads 23 toward the front E of the machine resulting in moving the drum 25 away from the drum 20. The drums now occupy the relative positions shown in Figures 4 and 7. The operator withdraws the pin or spindle 56 from the outlet pipe and the latter is removed from the recess 55 in the supporting block 54. The lengthwise strings 15 are applied to the filter pack by another machine or operation.

As previously stated, the spacing of the movable plate 43 from the stationary plate 42 determines the length of the pack to be formed. When a longer or shorter pack is desired, the plate 43 is adjusted relative to the fixed plate 42, and an endless belt of the proper width is trained over the drums 20 and 25.

Brief description of operation

Having thus described the various structural features of my oil filter pack-making machine, the operation thereof may be briefly summarized as follows:

The filter core B is supported in the depressed portion 35 of the endless belt D, with the outlet

pipe 5 of the core disposed at the bottom of the slot 53. The protruding end of this pipe extends into the recess 55 of the supporting block 54, and the spindle 56 projects into the bore of the pipe to rotatably support the filter core.

Now the drum 25 is moved into the position shown in Figure 3 by the operating handles 36 and the sliding crossheads 23. The notches 37 on these handles are engaged with the catches 38 (see Figure 2). At this time the driving gear 32 meshes with the gear 34. When the motor 26 is turned on, the drums 20 and 25 will rotate in the direction of the arrows 33 and 58, respectively, causing the belt D to move.

A predetermined amount of cotton waste, which has been weighed out for a pack, now is fed into the space defined between the filter core and the portion d of the belt. This incoming waste is wrapped in layers around the core filter B by the movement of the endless belt and the free rotation of the filter core. The cotton waste is compressed around the core, and the operator feeds the waste so as to cover the entire distance between the plates 42 and 43. The density of the filtering material or cotton waste 10 will be uniform throughout the pack A, since a predetermined amount of the cotton waste is used for each, dependent upon the length and diameter of the pack and the density desired.

Next, the motor 26 is stopped for a short period of time while the free ends 14a of the strings 14 are placed lengthwise of the pack (see Figures 1 and 9). Intermediate portions of the strings, as at 14b, are engaged with the spiral spring 66 near the right-hand end of the machine. The motor is started up again, and rotation of the shaft 65 and turning of the pack will wrap the strings spirally around the compressed cotton waste.

The motor 26 is stopped and the strings 14 are cut near the left-hand end 12 of the pack. These cut ends then are tied to a previous winding of the string. The handles 36 are pulled outwardly, and this will separate the drum 25 from the drum 20 (see Figure 7). The oil filter pack A now may be withdrawn from the machine and is ready to have the lengthwise strings 15 applied thereto to complete the pack.

I claim:

1. In an oil filter pack-making machine, means for rotatably supporting a filter core, means for rotating the filter core and applying successive layers of a filtering material around the core and compressing these layers toward the core to provide a cylindrical oil filter pack, means for forming parallel opposing ends on the pack, and means for winding a string or the like spirally around the peripheral surface of the cylindrical pack for binding it permanently to the core.
2. In an oil filter pack-making machine, an endless belt having a depressed portion therein defining a loop, means for rotatably supporting a filter core in the loop with the loop portion of the belt spaced from the core, the loop having an open section therein through which filtering material may be introduced into the space between the core and the loop of the belt, and means for operating the belt to compress the filtering material upon the core to provide an oil filter pack.
3. In an oil filter pack-making machine, an endless belt having a depressed portion therein defining a loop, means for rotatably supporting a filter core in the loop with the loop portion of the belt spaced from the core, the loop having an open section therein through which filtering material may be introduced into the space between the core and the loop of the belt, and means for operating the belt to compress the filtering material upon the core to provide an oil filter pack.

the belt spaced from the core, the loop having an open section therein through which filtering material may be introduced into the space between the core and the loop of the belt, means for operating the belt to compress the filtering material upon the core to provide an oil filter pack, and means for binding a string or the like around the compressed filtering material while the pack is still disposed in the loop.

4. In an oil filter pack-making machine, an endless belt having a depressed portion therein defining a loop, means for rotatably supporting a filter core in the loop with the loop portion of the belt spaced from the core, the loop having an open section therein through which filtering material may be introduced into the space between the core and the loop of the belt, means for operating the belt to compress the filtering material upon the core to provide an oil filter pack, means for binding a string or the like around the compressed filtering material while the pack is still disposed in the loop, and means for opening up the loop to free the bound pack from the belt.

5. In an oil filter pack-making machine, an endless belt having a depressed portion therein defining a loop, plates arranged at opposite sides of the belt and forming end walls for the loop, means for rotatably supporting a filter core in the loop with the loop portion of the belt spaced from the core, the loop having an open section therein extending between the plates through which filtering material may be introduced into the space between the core and the loop portion of the belt, and means for operating the belt to compress the filtering material upon the core to provide a cylindrical oil filtering pack.

6. In an oil filter pack-making machine, an endless belt having a depressed portion therein defining a loop, plates arranged at opposite sides of the belt and forming end walls for the loop, means for rotatably supporting a filter core in the loop with the loop portion of the belt spaced from the core, the loop having an open section therein extending between the plates through which filtering material may be introduced into the space between the core and the loop portion of the belt, means for operating the belt to compress the filtering material upon the core to provide a cylindrical oil filtering pack, means for adjusting the plates relative to one another to form packs of various lengths, and means for binding a string or the like spirally around the compressed filtering material throughout the entire length of the pack.

7. In an oil filter pack-making machine, an endless belt having a depressed portion therein defining a loop, plates arranged at opposite sides of the belt and forming end walls for the loop, means for rotatably supporting a filter core in the loop with the loop portion of the belt spaced from the core, the loop having an open section therein extending between the plates through which filtering material may be introduced into the space between the core and the loop portion of the belt, means for operating the belt to compress the filtering material upon the core to provide a cylindrical oil filtering pack, means for adjusting the plates relative to one another to form packs of various lengths, and means for binding a string or the like spirally around the compressed filtering material throughout the entire length of the pack, while the pack is still disposed in the loop between the plates.

8. In an oil filter pack-making machine,

pair of rotatably-mounted drums arranged in parallel relation with each other, means for adjusting the drums toward and away from one another, an endless belt trained over the drums and having a depressed portion between the drums defining a loop when the drums are positioned in adjacent relation, plates arranged at opposite sides of the belt and forming end walls for the loop, means for rotatably supporting a filter core in the loop with the loop portion of the belt spaced from the core, the loop having an open section between the drums and extending between the plates through which filtering material may be introduced into the space between the core and the loop portions of the belt, and means for operating the belt to compress the filtering material upon the core to provide a cylindrical oil filtering pack, the latter being releasable from the loop when the drums are moved apart.

9. In an oil filter pack-making machine, means for rotatably supporting a filter core, means for applying and compressing filtering material around the core while the latter is rotated to form a cylindrical oil filter pack, a revolvable shaft mounted parallel to the axis of the pack and having a spiral-shaped string-guide thereon, one end of the string being securable to the pack and the string-guide being arranged to guide the string along the compressed material when the shaft and pack are rotated, and means for turning the shaft to bind the pack with the string.

10. In an oil filter pack-making machine, an endless belt of a predetermined length, a pair of rotatably-mounted drums arranged in parallel relation with each other, the belt being trained around the drums and having a looped portion in one reach and lying between the drums and extending toward the other reach of the belt, means for rotatably supporting a filter core in the loop with the core being spaced from the belt portion forming the loop, the loop having an open section through which filtering material may be introduced into the space between the core and the loop portion of the belt, and means for rotating the drums for causing the loop portion to wrap and compress the material around the core to form a cylindrical mass, the fixed length of the belt and the bearing of the loop against the said other reach determining the density of the pack when a predetermined quantity of the material is fed into the loop.

11. In an oil filter pack-making machine, means for supporting a hollow filter core with freedom of rotation, means for wrapping a predetermined quantity of filtering material around the rotatable core with a predetermined compressive force, and means for winding a string or the like around the packed filtering material to secure the latter permanently to the filter core.

12. In an oil filter pack-making machine, means for supporting a filter core with freedom of rotation, means for wrapping a filtering material in layers around the rotatable core and compressing the successive layers onto the filter core with a predetermined compressive force to provide an oil filter pack of a predetermined diameter and density, and means for winding a string or the like about the periphery of the pack to secure the compressed filtering material permanently to the filter core.

13. In the herein described method of forming cylindrical filtering packs with all of the packs

having a uniform density of filtering material, the steps of weighing out a predetermined amount of filtering material, winding this material in layers around a rotatably supported filter core while arranging the material throughout the length of the pack to be formed in order to obtain a uniform density, compressing the material to a predetermined extent into a cylindrical shape of a predetermined diameter, and winding a string spirally around the pack while the latter is held in a compressed state.

14. In the herein described method of forming oil filtering packs with all of the packs having a uniform density of filtering material; the steps of weighing out a predetermined amount of filtering material for each pack; winding this material in layers around a filter core, while distributing the material uniformly throughout the entire length of the pack being formed; uniformly compressing the successive layers of

5 material as they are wound on the core to a predetermined extent by uniform pressure applied against the periphery of the pack being made toward the core; and binding the periphery of the pack to secure and maintain the compressed material permanently to the core.

ALBERT R. WHITE.
